United States Patent Office.

FRANCIS M. FRANKLIN, OF SPRINGFIELD, OHIO, ASSIGNOR TO HIMSELF AND EDWARD M. DOTY, OF SAME PLACE.

Letters Patent No. 91,109, dated June 8, 1869; antedated May 24, 1869.

IMPROVEMENT IN PLOWS.

The Schedule referred to in these Letters Patent and making part of the same.

To all whom it may concern:

Be it known that I, FRANCIS M. FRANKLIN, of Springfield, in the county of Clarke, and in the State of Ohio, have invented certain new and useful Improvements in Plows; and do hereby declare that the following is a full, clear, and exact description thereof, reference being had to the accompanying drawings, and to the letters of reference marked thereon.

The nature of my invention consists in the construction of the sheath to a plow, and in the manner of attaching the plow-beam to the handle.

In order to enable others skilled in the art to which my invention appertains, to make and use the same, I will now proceed to describe its construction and operation, referring to the annexed drawings, which form a part of this specification, and in which—

Figure 1 is a side view, and

Figure 2, a front view.

A represents the plow-beam, B, the handle, and C, the sheath, to which the plow D is secured, said plow being shown in fig. 1 in red lines.

The sheath C is of the usual length and size, of round wrought-iron, vertical, with a forward curvature.

At the height of about eleven inches it bends out from the line of the beam; then, at the additional height of about five inches, it has a right angle, bent across the line of the beam. This horizontal part of the sheath I term "a knee;" it is about four inches long. The beam rests on about three inches of the knee, and the projecting inch is flat, and has a hole through it, from which a brace, or braces, E, extend to one or both handles, or to a suitable point on the mould-board.

The front of the draught-rod F has an eye, for a ring, G, and back of said eye, for a suitable distance, the draught-rod is flat, and secured to the point of the beam A by one or more screw-bolts.

The rear end passes through an eye in a bolt, H, which passes up through the beam just in front of the knee on the sheath C.

The draught-rod F has a bend just back of said knee, and passes up through the beam. Thus the rod F and bolt H, each having a washer and nut, form a stirrup, to keep the beam firm to the knee.

By this arrangement the draught-rod becomes a support to the beam in a greater degree than can be obtained by any former mode of attachment, thus gaining the advantage at this point of adding the power of tension to the strength of the beam, through the medium of the angle.

Upon the handle B, at a proper distance below the

level of the knee, an upright, I, is attached by screw-bolts.

The lower end of the upright, I, is flat, and the bolts pass through holes in that part, to secure it to the handle. Just above the flat part, the upright angles, incline a little forward. A screw is cut on the upright, to the height of about five inches.

A nut, a, is run down to the flat, and the upright passes up through a hole a suitable distance from the rear end of the beam. The direction of this hole, and the position of the upright should be decided by a tram pivoted on the centre of the knee.

The upright, I, projects above the beam, to receive a washer and nut, b.

Above the nut b the upright is reduced in thickness, and passes through the end of a forked brace, J, and has a nut, c, above said brace.

The forks of the brace J extend back, one passing on each side of the beam-handle B, and have holes in their rear ends, through which an iron round, L, passes, going also through both handles, and through two thimbles, d d.

The thimbles d d are bell-shaped, and placed between the handles and the ends of the brace, the large ends against the handles, and the smaller, outer ends, against the brace. The thimble and brace between the handles are pressed against the handle by a firm washer, e, on the round L; those outside are kept to the handle by a nut, f, on the end of the round.

It will be seen, that by raising or lowering the rear end of the beam A, on the upright, I, by means of the nuts a and b, the height of the plow is easily regulated.

Having thus fully described my invention,

What I claim as new, and desire to secure by Letters Patent, is—

1. The bent sheath C, constructed and used substantially as and for the purposes as herein set forth.

2. The arrangement of the beam A, sheath C, bent draught-rod F, eye-bolt H, upright, I, and handle B, all substantially as shown and described.

3. The arrangement of the handle B, upright, I, round, L, forked brace J, thimbles d d, washers e e, and nuts c and f f, all substantially as herein set forth.

In testimony that I claim the foregoing, I have hereunto set my hand, this 30th day of May, 1868.

FRANCIS M. FRANKLIN.
